REFUSE DESTRUCTOR

John E. Allen, Michael J. Blew, and Albert C. Wood, Philadelphia, Pa.

Application July 3, 1930, Serial No. 465,566

4 Claims. (Cl. 110—14)

Our invention is an improved refuse destructor designed particularly for the dehydration and incineration of wet sludges containing a considerable amount of combustible material, and 5 leading objects of our invention are the avoidance of caking or balling during dehydration, the elimination of offensive odors resulting from combustion and the utilization of the heated products of combustion in an efficient manner in dehydrating 10 further refuse and heating air for carrying on combustion so as to minimize the amount of supplementary fuel required in the operation of the destructor. Further objects of our invention are the provision of destructor apparatus of 15 simple and rugged construction which can be economically erected and operated, which occupies relatively little floor area, and in which the refuse material may be dried at a rate compatible with its character.

20 In the preferred embodiment of our improvements, a metallic drum is revolvably supported adjacent to its ends by peripheral tires carried by suitable rollers. The intermediate section of the drum is housed within a furnace chamber through 25 which heated gaseous products of combustion are diffused by vanes on the drum. Such gaseous products of combustion may be deodorized by passage through a highly heated refractory checker work or regenerator and after discharge 30 from the chamber surrounding the drum may be utilized for the preheating of air for carrying on combustion. The heated air is discharged through a grate to which fuel may be fed and to which the drum discharges dehydrated refuse 35 dried by its passage through the drum which contains agitators, preferably consisting of heavy chains and ploughs, for preventing caking or balling of the refuse and facilitating its movement through the drum. The rate at which the 40 refuse is introduced into the drum may be regulated by a mechanical feeder.

The characteristic features and advantages of our improvements will further appear from the following description and the accompanying 45 drawing showing an illustrative embodiment of our invention.

In the drawing Fig. 1 is a longitudinal sectional view of a refuse destructor embodying our improvements; Fig. 2 is a view taken transversely 50 to Fig. 1 looking toward the discharge end of the drum and partly in section and partly in elevation; and Fig. 3 is an enlarged detailed transverse sectional view of the drum and agitating chains.

55 As illustrated in the drawing, a furnace setting

1 of suitable refractory material forms a furnace 2 and a drum chamber 3 divided therefrom by a refractory checker work baffle 4 which retards the passage of combustible gases and effects thorough admixture therewith of burned out 5 gases. The furnace contains an inclined grate 5 to which access may be had through the fuel door 6.

A drum 7 has fixed thereon tires 8 which roll 10 on rollers 9—9'. The intermediate section of the drum is disposed in the chamber 3 and one end thereof discharges into an upper portion 2' of the furnace 2. Access to the compartment 2' and to the drum 7 may be had through the man-hole 10 normally closed by the cover 11. The joints 15 between the drum and the walls of the furnace setting may be sealed by flanges 12 disposed in the annular grooves 13 on the drum.

The inlet end of the drum is provided with a header 14 having an axial opening for the passage 20 of a spout 15 which makes a sealed joint with the header and to which regulated amounts of refuse are delivered by the adjustable rotary pocket feeder 16 supplied from the hopper 17.

A series of heavy non-fouling chains 18, certain 25 of which are indicated in Fig. 3 and all but one of which are omitted in Fig. 1 for clearness are hung on eyelets 18a at frequent intervals around the inner periphery of the drum and along the length thereof, and a series of vanes or ploughs 30 19 are fixed within the drum, particularly adjacent to the outlet end thereof. The chains and ploughs agitate and break up the mass of sludge and prevent the adherence thereof to the walls of the drum, and the inclined ploughs 19 35 also facilitate the movement of the dried products through and from the drum.

The external periphery of the drum section within the chamber 3 has welded thereto a series 40 of narrow steel plates 20 to augment the absorption of heat from the gases through the drum or shell, and also to diffuse the gases through the chamber 3 so as to heat all parts of the drum and supplement the action of the arches 21 in preventing direct flow of the heated gases to the stack 22. The stack 22 contains air preheater tubes 23 through which air is forced by the blower 24 through the conduit 25. A conduit 26 communicating with the bottom of the preheater delivers the heated air through the port 27 to 50 the ash-pit 28 below the grate 5.

It will be understood that in the operation of the apparatus a bed of incandescent matter is maintained upon the grate 5, such matter consisting either of previously dried refuse or sup- 55

plementary fuel introduced through the fuel port 6 or both. The sewage or sludge is supplied to the hopper 17 and the feeder 16 is rotated to feed the sludge at any desired rate to the inlet end 5 of the drum. The drum is rotated by any suitable means through the sprocket or gear 29 and the sludge is fed through the drum. The sludge is dried both by the application of heat externally to the drum in the chamber 3 and to some extent by direct action of heat radiating from the 10 passage 2' into the drum. The chains 18 break up and agitate the sludge as the drum is rotated, and when the partially dried sludge reaches the ploughs 19 it is further broken up and its passage 15 through the drum facilitated. The dried refuse is discharged from the discharge port of the drum into the furnace 2 where it is burned on the grate 5 and the passage of gaseous products of combustion from the furnace are retarded by the checker work baffle 4 until they have been deodorized, when they pass into the drum chamber 3 to heat and dry further refuse passing 20 through the drum. The deodorized and partially cooled gases then pass to the stack 22 where they are further cooled as a result of absorption of 25 heat therefrom by air forced through the pre-heater 23 by the blower 24. Such heated air is then discharged to the furnace 2 to provide air for the combustion of the matter in the furnace. Should the refuse contain insufficient 30 readily combustible matter to maintain the desired temperature, supplementary fuel may be introduced from time to time through the port 6.

Having described our invention we claim:

- 35 1. A refuse destructor comprising a cylindrical rotatable drum, means including a grate for heating the drum, means at opposite ends of the drum for feeding refuse to, and discharging it from the drum, the grate receiving the discharge, eyelets secured to the inner surface of the drum 40 in circumferential and longitudinal staggered relation for a distance from the feed end of the drum, and chains each secured only at one end and to one of said eyelets, said discharge means including ploughs secured to the inner surface, 45 near the discharge end, of the drum.

2. A refuse destructor comprising a rotatable drum, roller supports adjacent to the ends thereof, a furnace having a chamber in which an inter-

mediate portion of the drum is housed, vanes on the drum diffusing gaseous products of combustion through the chamber, means including a highly-heated open refractory checker work in said chamber for deodorizing said products, 5 means receiving said products after discharge from said chamber for preheating air for carrying on combustion in the furnace, a grate to which the drum discharges dehydrated refuse, said air discharging through said grate, agitator chains 10 and ploughs in the drum preventing caking of the refuse and facilitating its movement through the drum, and mechanical feeder means for regulating the introduction of refuse to the drum.

3. A refuse destructor comprising a drum movable about an axis passing therethrough, means for feeding refuse into the drum at one end thereof, a furnace to which said drum discharges at its other end, means forming a chamber surrounding a portion of said drum and to which 20 said furnace discharges, a flue leading from said chamber, said drum having an exposed portion between said furnace and means, supports without said chamber and engaged by said drum, said drum rotating on said supports, and means 25 mounted on said drum and rotatable therewith to disseminate products of combustion from said furnace through said chamber.

4. A refuse destructor comprising a drum movable about an axis passing therethrough, means for feeding refuse to the drum, chains suspended from the inside periphery of said drum, a propelling device disposed in said drum, a grate to which said drum discharges, a refractory checker work at the opposite end of said grate from said 35 drum discharge and to which heated products of combustion are discharged from said grate, means forming a chamber surrounding said drum and to which said checker work discharges, baffles fixed to said drum and increasing the heat 40 absorption thereof and dispersing gaseous products of combustion through said chamber, a flue leading from said chamber and an air preheater operatively associated with the flue and connected to deliver preheated air below said grate. 45
